UNITED STATES PATENT OFFICE

136,023

DESIGN FOR A KITCHEN UTILITY KNIFE

Solomon Barr Phillips, Waterbury, Conn.

Application May 6, 1943, Serial No. 110,138

Term of patent 7 years

To all whom it may concern:

Be it known that I, Solomon Barr Phillips, a citizen of the United States, residing in the city of Waterbury, county of New Haven and State of Connecticut, have invented a new, original, and ornamental Design for a Kitchen Utility Knife, of which the following is a specification, reference being had to the accompanying drawing forming a part thereof, in which:

Fig. 1 is a plan view of my new design of kitchen utility knife;

Fig. 2 is a side view thereof; and

Fig. 3 is an end view of said design.

I claim:

The ornamental design for a kitchen utility knife, as shown.

SOLOMON BARR PHILLIPS.
